UNITED STATES PATENT OFFICE.

EDWARD DAUM, OF OKATON, SOUTH DAKOTA.

LID FOR STOVES.

1,164,995.

Specification of Letters Patent. Patented Dec. 21, 1915.

Application filed July 23, 1913. Serial No. 780,753.

To all whom it may concern:

Be it known that I, EDWARD DAUM, a citizen of the United States, residing at Okaton, in the county of Lyman and State of South Dakota, have invented new and useful Improvements in Lids for Stoves, of which the following is a specification.

This invention relates to lids for stoves of various kinds and especially for cooking stoves and ranges.

The invention has for its object to produce a lid having passages for the circulation of air which during its passage becomes heated and is discharged upon the fire, thereby promoting combustion to such an extent that a large proportion of the products usually escaping in the form of smoke will be consumed and a corresponding amount of fuel saved.

A further object of the invention is to produce a lid of the character described which will be simple, inexpensive and easily applied to any stove or range.

A further object of the invention is to simplify and improve the construction of the lid and the assembling of the parts thereof.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alteration and modifications within the scope of the device as claimed may be resorted to when desired.

In the drawings, Figure 1 is a top plan view of a lid constructed according to the invention. Fig. 2 is a side elevation of the same. Fig. 3 is a top plan view with the top or cover plate detached. Fig. 4 is a bottom plan view, partly in section, with the bottom plate detached. Fig. 5 is a sectional view taken on the line 5—5 in Fig. 3.

Corresponding parts in the several figures are denoted by like characters of reference.

The improved lid in its preferred construction, as here illustrated, is composed of three principal parts or members, namely, a top or cover plate A, a bottom plate B and

an intermediate body member C. The body member C is composed of a cylindrical rim or annulus 15 having about midway between its upper and lower ends a diaphragm 16 on the upper side of which a plurality of substantially L-shaped channels 17 are formed, the walls of said channels being composed in part of flanges 18 rising from the diaphragm and radiating from a central annular flange 14, and partly of portions of the rim 15. The L-shaped channels may be described as being disposed in circumferential series, and two of said channels which are specifically designated by 17^a and 17^b may be regarded and will be described as being the first and the last of the series. The first channel 17^a communicates at its inner end, that is to say, near the center of the lid, with an intake opening 19 formed in the top plate A, and into said opening is threaded an intake pipe 20 which is curved to form an upwardly extending arched portion 21 and a straight portion 22, the latter lying flat on the surface of the top member A and having its end cut off obliquely, as seen at 23, for the ready admission of air, while the arched portion 21 will prevent any liquid that may boil over from pots or kettles from entering through the intake pipe. The outer terminal of each channel communicates through an opening 24 lying adjacent to the rim 15 with one of a series of compartments 25 formed on the underside of the diaphragm by flanges 26 radiating from a central annular flange 27. Each compartment 25 communicates through an opening 26' with the inner end of the next channel 17 of the series. The last channel of the series, 17^b, is provided with a return flange 27' that communicates at its inner end through a special opening 28 with the last compartment of the series which is specially designated as 25^b, and the portion of the rim 15 which constitutes the outer wall of said compartment 25^b is provided with apertures 29 for the escape of heated air.

The top plate A, the bottom plate B and the intermediate body member C are assembled together by means of bolts 30 for the passage of which suitable apertures are provided, and it will be seen that when the parts are thus assembled, the bottom plate affords a closure for the lower ends of the compartments 25, 25^b, while the top plate A constitutes a closure for the upper ends of the channels 17, 17^a and 17^b. The top plate

A has been shown as provided with a recess 31 having lugs 32 to be engaged by an ordinary lid lifter.

In the operation of this device, the improved lid is placed on the stove or range above the fire. Air entering through the intake pipe 20 will circulate through the channels and through chambers or compartments provided for the purpose above and below 10 the diaphragm 16, and in the respective compartments 25 the air will be permitted to expand and will be subjected to the intense heat from the fire. From the branch 27' of the last channel 17^b of the series, the 15 heated air will be discharged into the last compartment 25^b near the inner end of the latter, and the air after passing through said compartment will escape through the apertures 29 and be discharged upon the fire 20 with the effect of promoting combustion to a very appreciable extent. The construction of the improved device is very simple and inexpensive, it being composed of three simple castings assembled together by means 25 of ordinary stove bolts. It may obviously be made of different sizes to fit the holes of stoves and ranges of various dimensions.

Copies of this patent may be obtained for five cents each, by addressing the "Commissioner of Patents, Washington, D. C."

Having thus described the invention, what is claimed as new, is:—

1. An air heating and circulating fuel saving stove lid, the same including a top plate having an intake opening and a pipe threaded into said opening, said pipe being provided with an upwardly curved arched portion to exclude liquids from the intake 35 opening.

2. An air heating and circulating fuel saving stove lid having air circulating channels and chambers, said lid including a top plate having a vertical intake opening, a 40 circumferential rim having exit openings, and an intake pipe threaded into the intake opening, said pipe having an upwardly curved arch portion to exclude liquids from the intake opening, and a horizontally disposed portion resting on the top plate, said horizontally disposed portion being cut off obliquely at its outer end.

In testimony whereof I affix my signature in presence of two witnesses.

EDWARD DAUM.
